CENTRALIZED TRAFFIC CONTROLLING
AND COMMUNICATING SYSTEM FOR
RAILROADSWilliam D. Hailes, Brighton, and Frederick W.
Brixner, Gates, N. Y., assignors to General
Railway Signal Company, Rochester, N. Y.

Application May 8, 1940, Serial No. 334,022

31 Claims. (Cl. 179—2)

The present invention relates to a centralized traffic controlling system of the coded type upon which is superimposed a telephone system with selective ringing of the coded type.

In the application of centralized traffic control to a railway system through the medium of which switches and signals may be controlled at many distant points along the railway through the medium of codes transmitted over a single line circuit it is often found that communication by telephone is necessary over the same territory, and in accordance with the present invention it is proposed to carry out centralized traffic control and telephone communication over the same pair of line wires. In one particular type of centralized traffic control of the coded type distinctive control codes are transmitted from a central office to any one of a large number of field stations by the transmission of a large number of impulses for each code, which impulses are arranged in a code pattern wherein the code characters reside in the distinctive polarity of these impulses and wherein indications are transmitted from any one of these field stations to the central office through the medium of codes each comprising a large number of impulses in which these impulses are distinctive by being either long or short or by having the time spaces between these impulses distinctive by being either long or short. One form of such centralized traffic control system is disclosed in applicants' prior application Ser. No. 197,404 filed March 22, 1938, now Patent No. 2,259,561 granted Oct. 21, 1941.

In this particular prior application a first series of impulses in each control code cycle is employed to select a particular field station by picking up a station selecting relay and in a second series of such impulses particular traffic controlling devices at such field station are controlled and during the last impulse of such series the station selecting relay at the station selected is again deenergized, so that the station selecting relay as therein used cannot be used after the control code for the field station has been completed. Also, in this particular type of centralized traffic controlling system there are provided cycle marking relays which are slow dropping and which will remain up during intermittent deenergization of the line circuit but which will be released during a long period of deenergization of the line circuit. Furthermore, this particular type of centralized traffic controlling system includes apparatus in the office whereby when the desired number of control impulses have been transmitted to the

field station the control office leaves the line circuit deenergized thereby dropping the cycle marking relays at the control office and at each one of the field stations after which the line circuit is again energized.

In accordance with the present invention it is proposed to modify this particular type of centralized traffic controlling system of said Patent No. 2,259,561 by employing a special circuit in the control office for holding the negative pulsing relay NC energized when the last stepping relay LV in the control office is energized only under those conditions when it is desired to transmit a telephone code over the line circuit after the particular field station at which this telephone code is to be employed has been selected (see branch circuit in heavy lines including front-contact 427 of relay LV and front contact 587 of relay CDT! Figs. 1A and 7A). It is further proposed in accordance with this invention to employ a secondary or telephone station selecting relay at such field station at which a telephone code is to be received, this secondary station selecting relay being energized in response to the energization of the last stepping relay LV at such field station, this supplemental or telephone station selecting relay remaining energized so long as the line circuit remains either intermittently or continuously energized (see relay 4SOT Figs. 1B and 7D). It is further proposed in accordance with the present invention to employ a supplemental code determining relay in the control office for the panel for each way station to which a telephone code is to be transmitted, this supplemental code determining relay 35 CDT being interlocked with all of the other code determining relays CD so that only one code determining relay can be energized at any one time, this code determining relay being employed to render the coding key, such as key K1A (Figs. 1A, 2 and 7A), effective to transmit a telephone calling code at the end of the station selecting and control code, providing that the operator in the control office in response to the sounding of a 40 buzzer has operated a coding key, such as K1A (see relay CDT!). Another object of the present invention resides in the provision of such a buzzer which is sounded when a particular station has been selected by the centralized traffic controlling system for the purpose of transmitting a 45 telephone code to such system, together with means for silencing such buzzer when the operator has operated and released a telephone coding key for transmitting a telephone code to the selected field station (see buzzer BUZ).

Another object of the present invention resides in the provision of suitable filtering apparatus which enables a telephone communication to be carried on over the wires of the centralized traffic controlling system during the transmission of a centralized traffic control code or indication code or the transmission of a telephone calling code without interfering with the audibility of the telephone communication, this filtering apparatus being constructed to perform its functions irrespective of whether the centralized traffic transmitting code is a control code or an indication code and irrespective of whether a particular lock-out relay LO is then energized and irrespective of whether the line is then being coded by a coding relay, such as relay E at the field the same or some other field station, this result being accomplished irrespective of whether the telephone communication is carried on between the office and the telephone located beyond the transmitting field station or whether the transmitting field station is beyond the station at which the telephone then in use is branched off.

Other objects, purposes and characteristic features of this invention will in part be pointed out in the specification hereinafter and will in part be obvious from the accompanying drawings, in which:

Fig. 1A discloses rather conventionally the office apparatus of the composite centralized traffic control code and telephone code system;

Fig. 1B illustrates the line circuit of such system together with two field station equipments;

Fig. 2 shows a telephone coding key an element of the present invention;

Fig. 3 shows the telephone selector S1A of the telephone system superimposed on the centralized traffic controlling system;

Figs. 4, 5 and 6 show the telephone selector of Fig. 3 energized negatively, positively and deenergized respectively.

Figs. 7A and 7B illustrate the office apparatus disclosed in our prior application above referred to except that the push button B2, the change relay CH2, and the code determining relay CD2 have been omitted therefrom, and that additional apparatus embodying the improvements of the present invention over that of the invention in said patent has been superimposed thereon. All of the relays, devices and circuits of said prior application being shown in light lines, whereas the superimposed apparatus and circuits have been shown in heavy lines;

Figs. 7C and 7D illustrate a field station apparatus of our said prior application in light lines having superimposed thereon in heavy lines the necessary wiring and apparatus for selectively ringing a telephone station and for carrying on a telephone communication over said system during the transmission of a traffic controlling, traffic indication or a telephone calling code; and

Fig. 8 illustrates a modified construction of that part of the line circuit located in the control office.

C. T. C. office apparatus

Since the office equipment of the centralized traffic controlling system has been described in detail in our above mentioned patent this apparatus will only be briefly described herein. In order to distinguish the wiring and apparatus disclosed in our said patent from the apparatus that has been added to disclose the combination embodying our present invention the apparatus of such patent is shown by light lines, 75

whereas the added apparatus and circuits are shown by heavy lines.

Referring to Figs. 7A and 7B, when laid one above another with the stepping relays in registration, disclose by the light lines contained therein the office equipment shown in Figs. 2 and 3 of our said patent. This apparatus includes line wires 10 and 18 extending from the office to the field stations (see also Figs. 7C and 7D). These line wires may be energized by current of positive polarity when the pulsing relay PC is energized and may be energized by current of negative polarity when the pulsing relay NC is energized, and will be so energized if either the relay CO (designated relay C in said patent) or the relay CF is energized or if the relay OR is deenergized. These pulsing relays PC and NC may be energized in many different ways as indicated by the circuits shown in Fig. 7A, but for the purpose of transmitting a particular code for selecting the first field station consists of a pattern of positive and negative current impulses selected over code jumpers 67, 70 and 72, and are controlled over similar code jumpers arranged to modify the order of these impulses when some other field station is to be selected.

This office equipment also includes cycle marking and repeater relays SA, SB, SC, SD and OC all controlled in a manner as described in detail in our said patent above identified. The office equipment also includes a line relay F and a line repeater relay FA. The stepping relays V1, V2, V3, V4 and the last stepping relay LV are controlled in a well known manner and as disclosed in our said patent through the medium of a contact 92 of the half-step relay VP, the back contact 91 of the line repeater relay FA and the front contact 93 of the cycle marking repeater relay SC. These stepping relays V determine by their contacts 61, 62, 63 and 64 each in combination with its particular jumper such as 67, 70 or 72, whether such contact shall be effective to control the pulsing relays PC or NC, these jumpers however being ineffective unless their associated code determining relay, such as relay CD1, is energized. In order to energize one of these code determining relays, such as CD1, a change relay, such as relay CH1, has been provided. Each of these change relays may be picked up, as by a push button B1, and if once picked up is stuck up as through the medium of back contact of its associated code determining relay, such for instance, as back contact 40 of the code determining relay CD1 for the change relay CH1.

Briefly stated the office apparatus of the CTC system may apply to the line circuit a code made up of an assortment of positive and negative impulses in a manner as presently described. For instance, if the operator depressed the push button B1 he will pick up the change relay CH1 which will then stick up through the back contact 40 of the code determining relay CD1. With the change relay CH1 up its closed front contact 45 will close an energizing circuit for the code determining relay CD1, which includes back contact 41 of relay SC, back contact 42 of relay CF, back contact 43 of relay CDS, back contact 571 of relay CH1, front contact 45 of change relay CH1 and the normally closed push button contact 39 of the cancelling push button CNB. As soon as the code determining relay CD1 has been picked up the closure of its front stick contact 47 closes a stick circuit including the lower winding of this code determining relay

CD1 and including in series therewith the winding of the relay CDS and including in multiple back contacts 46, 48 and 49 of the relays LV, CO and SC, respectively. Picking up of the relay CDS closes an energizing circuit for the relay CO which includes back contact 50 of relay SC, front contact 51 of relay CDS, and back contact 52 of relay CF. Picking up of this office start relay CO (designated C in our said prior application) causes closure of its front contact 10 in the line circuit 10-18 thereby shunting the stick contact 21 of the line relay F, so that this line relay F becomes a non-stick relay instead of a stick relay as is the case when the apparatus is in its normal non-signalling condition. The office apparatus is now in condition to apply a series of impulses to the line circuit 10-18, these impulses characterizing a code as determined by the jumpers rendered effective by energization of the code determining relay CD1, and this code is of a character to render effective the apparatus at the field station No. 1 shown in Figs. 1B, 7C and 7D. For a more complete description of the C. T. C. apparatus shown in Figs. 7A and 7B reference should be had to our patent above referred to.

In addition to the apparatus above mentioned the office is provided with a miniature track layout including a miniature track switch ts, a switch machine control lever SML1, decoding relays TON, TOF, LON and LOF and a pulsing repeater relay EP.

C. T. C. field station apparatus

Referring now to Figs. 7C and 7D of the drawings, these drawings when laid side by side illustrate the apparatus located at an intermediate field station of the present invention and the relays, devices and circuits which are shown in light lines show the apparatus disclosed in Figs. 5A and 5B of our said patent.

Referring to Figs. 7C and 7D attention is directed to the fact that the line relay 1F is of slightly modified construction from that of the line relay shown in our said patent, in that a double winding relay has been illustrated of which one winding is included in series with one of the two line wires and the other winding is included in series with the other line wire of the C. T. C. system. Attention is also directed to the fact that the lock-out relay 1LO and the line pulsing relay 1E create double makes and double breaks in the line wires of the system in the present application as distinguished from single makes and single breaks in the said patent. The double winding for the relay 1F and the double contacts for the relays 1LO and 1E have been resorted to in order to result in an equal potential and impedance gradient along each line wire of the two line wires 10 and 18 irrespective of induction from other circuits, other foreign sources or the sudden making and breaking of the circuit by various relays. For instance, the impedance of the two windings of the relay 1F are substantially identical so that even though there is a sudden change in current due to an external influence, such as lightning or a sudden change of current in an adjacent circuit, there will be substantially no potential difference across the lines 10 and 18 due to the induced current. Similarly, opening of the line circuit by one of the relays, such as relay 1LO or 1E, will cause a break to occur in both wires at the same time, thus maintaining the impedance of each line wire in approximate bal-

ance with that of the other line wire and thereby limiting to a negligible value the potential difference which may appear across lines 10 and 18 due to currents induced in these lines by external sources just prior to such break.

The field station apparatus insofar as the centralized traffic control features thereof are concerned includes a station selecting relay 1SO and an associated relay 1SOS. These relays are picked up at the beginning of a control cycle in a manner as fully described in our said patent and these relays will remain energized only so long as the successive polarity code impulses transmitted to such field station from the office are in an order in conformity with the code assigned to that field station. For instance, suitable code jumpers, such as code jumpers 149, 141 and 142, are provided at each field station, these code jumpers are connected to enable current to flow from the polar contact 30 of the line relay 1F to these relays 1SO and 1SOS only if the polar position of this contact 30 conforms to the positions assigned to the jumper 149, 141 or 142. For instance, since the code jumper 142 is positioned in its lowermost position the contact 30 of the relay 1F must be in its left-hand position when the stepping relay V3 is energized. Similarly, this contact 30 must be in its right-hand position when the stepping relays 1V or 2V is energized, this by reason of the fact that the jumpers 149 and 141 are in their upper position. In other words, the relays 1SO and 1SOS will receive pulses of current from the contact 30 of the line relay 1F only if the code pattern applied to the line circuit at the control office conforms to the code pattern as determined by jumpers 149, 141 and 142 in the field station. This relay 1SO is maintained energized between impulses through the medium of the back contact 138 of the line repeater relay 1FA, but relay 1SOS drops during an off period after relay 1FA drops. Also, the relay 1SO is maintained energized by another stick circuit through the front contact 152 of the stepping relay V4 during the time that the stepping relay V4 is up, namely, the time when a particular traffic controlling device at such field station, such as the relay SMR, is controlled. When, however, the code has proceeded to the last impulse, namely, the impulse period when the last stepping relay LV is energized the back contact 144 of this relay LV is opened so that the front contact 152 of the stepping relay V4 can no longer hold the relay 1SO energized, so that the station selecting relay 1SO will be deenergized and dropped during the next impulse period following the picking up of the last stepping relay LV. In order to maintain energy on this polar contact 30 of the relay 1F in the system of the present invention, which formerly was derived only through front contacts 125 of the relay 1SO or the back contact 29 of the relay 1SB, a new contact 501 has been added to the last stepping relay LV in multiple with these contacts 125 and 29. The purpose of this additional contact 501 will be described in connection with the field station telephone apparatus.

The C. T. C. field station apparatus also includes cycle marking relays 1SA, 1SB, 1S and 1OC. These relays are energized at the beginning of a control cycle or indication cycle and are maintained energized throughout such control or indication cycle, except that the relay 1OC is not deenergized between cycles if these cycles are in close succession. The various control cir-

cuits for these relays have been described in detail in our said patent to which attention is directed and for this reason will not be further described herein. It may, however, be pointed out that these relays ISA , ISB , IS and IOC are so controlled that they will remain energized after the completion of a control cycle which has been transmitted for the purpose of establishing telephone communication so long as the line circuit is either intermittently or continuously energized in a manner as pointed out hereinafter. It may be stated at this point that if the field apparatus shown in Figs. 7C and 7D is selected for the purpose of ringing a telephone bell, either at this station or on a branch line 15 extending from this station, the usual station selecting code call will be transmitted to result in the energization of the station selecting relays ISO and ISOS , so that these relays ISO and ISOS will remain energized to allow the stepping of the stepping relays V1 , V2 , V3 and V4 to continue until a pick-up circuit for the last stepping relay LV has been completed. After this point in the code cycle has been reached the station selecting relays ISO and ISOS will 20 be deenergized, as a result of which the last stepping relay LV is energized at only one of the field stations, namely, the field station which had its station selecting relay energized throughout the entire station selecting code cycle exclusive 25 of the last impulse which energized the relay LV at such station. It may also be pointed out that this additional impulse when a telephone bell is to be selected by a telephone selector at that particular field station is created in the control office 30 through a circuit including a front contact 427 of the relay LV at the control office. This impulse will remain on the line and will hold all of the cycle marking relays energized until the operator in the control office has in response to sounding of a buzzer in the office operated a telephone key belonging to that field station which in turn results in the transmission of a telephone selector code for selecting a particular telephone bell associated with the selected field 35 station.

In addition to the equipment at the field station already mentioned the field station equipment also includes a track layout including a track switch TS operated by a switch machine SM , protected by a detector track circuit including a relay T and having associated therewith signals which if all at stop will hold the signals-at-stop relay M energized. To manifest a change in the conditions of the track switch or in the relays T or M a change relay ICH and a change repeater relay ICHP have been provided. The field station equipment also includes a half-step relay IVP , coding relays ILON and LOF and a stick relay combination including relays IL and IRL . The relay IL is a series relay and is included in the stick circuit of the relay IRL and is provided with a back contact 35 included in the pick-up circuit of the relay IRL . Since, however, the pick-up circuit for the relay IRL is normally closed through contact 30 of line relay IF in its left-hand position the relay IL is normally shunted and momentary deenergization of the line circuit 10-18 and line relay IF will result in the picking up of the series relay IL and the relays IL and IRL will then both remain energized in series until a code cycle is under way to an extent to pick up the cycle marking relay ISB having a back contact 36 in the stick circuit including relays IL and IRL in series, at 75

which time both of these relays IL and IRL will drop. This stick feature is primarily employed to prevent picking up of a change repeater relay, such as ICHP , at any station after the L relays, such as IL , have been picked up due to a momentary deenergization of the line circuit. For a further detailed description of this field station apparatus attention is directed to our patent above referred to.

10

Office telephone apparatus

Referring again to Figs. 7A and 7B when laid one above another, the apparatus and circuits shown in light lines therein conform precisely to the apparatus and circuits shown in Figs. 2 and 3 of our said patent, except that the change relay CH2 and its associated code determining relay CD2 have been omitted. In place of these relays CH2 and CD2 have been substituted the telephone change relay CHT1 and the telephone code determining relay CDT1 . This telephone code determining relay CDT1 has also been provided with a code repeater relay CDTP1 . The office apparatus is also provided with a telephone code initiating relay SRB and a telephone coding relay SRA . These relays SRA and SRB are controlled by any one of a plurality of telephone code determining repeater relays, such as relay CDTP1 for instance, supplemented by one or more telephone coding keys, such as key K1A . The office apparatus has also superimposed thereon in addition to the apparatus disclosed in our said patent a buzzer BUZ , an office filter FILO and a telephone TELO including a receiver Re and a transmitter Tr .

The new circuits that have been added to the office apparatus to constitute the present invention include a special hold-over circuit for the relay OC including front contacts 578 and 589 of relays CDTP1 and SRB in multiple and front contact 579 of relay SB ; a special hold-over circuit for the pulsing relay NC including front contact 427 of relay LV and front contact 587 of relay CDT1 ; and a special hold-over circuit for the relay E including front contact 114 of the relay LV , front contact 590 of the relay CO , wire 591, front contacts 588 and 597 in multiple of relays SRB and CDTP1 , wire 596, and front contact 119 of relay VP . There are also other additional circuits, such for instance as, the telephone coding circuit including front contact 601 of relay CDTP1 , back contact 602 of relay CDT1 , front contact 603 of relay SRB and coding contact 604 of relay SRA , for energizing the pulsing relays PC and NC .

45

Field station telephone apparatus

Referring again to Figs. 7C and 7D it is now proposed to describe the apparatus that has been superimposed on the C. T. C. field station equipment illustrated in our said patent. All of the apparatus which is supplemental to that disclosed in Figs. 5A and 5B of our said patent has been shown in heavy lines in Figs. 7C and 7D of the instant application.

50

Referring to Figs. 7C and 7D when laid side by side the relay IF has been illustrated as a double winding relay instead of the single winding relay IF illustrated in our patent and just to the left of this relay has been illustrated a telephone TELI connected in series with the condenser C1 across the line wires 10-18. Although no particular apparatus has been shown in Figs. 7C and 7D for ringing the bell associated with the telephone TELI located

55

60

65

directly at the field station shown in these drawings it is proposed that a telephone bell may be sounded by the picking up of a neutral relay connected in the circuit and controlled in a manner similar to the manner in which the switch machine control relay SMR has been shown connected and controlled and to provide a bell energized and sounded through a front contact of such relay. In other words, in order to establish telephone conversation with a man located directly at the field station it is proposed to call such attendant to the telephone through the medium of a polarity code such as is used for controlling a switch machine or a signal and without the employment of a telephone coding key or a telephone selector such as conventionally illustrated at S1A and as shown in Fig. 3, and as will be described hereinafter.

Bridged across the line wires 10 and 18 at the field station shown in Figs. 7C and 7D is a telephone transformer T1 which is of the usual construction. A condenser C2 is used at a mid-point in its primary winding and a condenser C3 at a mid-point in its secondary winding to block out the coded direct current. The secondary winding of this transformer T1 is connected directly to the line which leads to a distant telephone location at which the telephone selectors S1A and S1B (see Fig. 1B) are located. The telephone line leading to the telephone selectors S1A and S1B is also fed from a relaying unit RUI. This relaying unit RUI relays the telephone code, which is transmitted from the office to the field station through the medium of the centralized traffic controlling system, from the contact 505 of line relay 1F to the distant telephone selector units S1A and S1B; this relaying unit RUI being selected by the telephone station selecting relay 1SOT. This relaying unit RUI comprises a battery 502, a coding relay FRA1 and a code initiating relay FRB1, together with a suitable filter FIL1 similar to the filter FILO at the central office (see Fig. 7B) comprising inductors I¹, I², I³, and I⁴, capacitors or condensers C4 and C5 and resistors R1 and R2 all arranged in the manner shown to provide what is known to the art as a low pass filter.

The code initiating relay FRB1 is a direct repeater relay of the telephone station selecting relay 1SOT, it being energized directly through a front contact 503 of this relay 1SOT. The coding relay FRA1 is energized through a circuit including the polar contact 505 of the line relay 1F and the front contact 506 of the telephone station selecting relay 1SOT in series, so that this telephone coding relay FRA1 is picked up each time that the C. T. C. line circuit 10-18 is energized by current of positive polarity so long as the station selecting relay 1SOT is energized. This station selecting relay 1SOT will be energized only if that field station has been selected by having its stepping relays operated through the entire cycle and to the point where the last stepping relay LV is energized. This circuit for the telephone station selecting relay 1SOT may be traced from the terminal (+) of a suitable source of current, front contact 501 of the stepping relay LV (the front contact 125 of the relay 1SO having dropped by opening of contact 144 when the relay LV is picked up), the polar contact 30 of the line relay 1F assuming either its right-hand or its left-hand position, the front contact 428 or 429 of relay LV, depending upon the polar position then assumed by the line relay 1F, through the winding of the

telephone station selecting relay 1SOT. This station selecting relay 1SOT is sufficiently slow dropping so that it will not be dropped during deenergization by pole changing of the C. T. C. line circuit resulting in movement of the contact 30 of the relay 1F from one extreme to the other extreme position.

Another addition to the field apparatus of Fig. 7C and 7D above that of the disclosure of our prior application resides in the provision of double contacts on the relays 1LO and 1E in the line circuit to make or break, as the case may be, the line circuit in both wires 10 and 18 at the same time. This function is performed by contacts 146 and 546 of relay 1LO and contacts 258 and 588 of relay 1E. When the lock-out relay 1LO is energized the line circuit may be intermittently closed by the pulsing relay 1E through the shunt path including the inductances I8 and I9 and the resistance R8 in series. The resistance R8 has an ohmic value substantially equal to the resistance of that part of the line circuit for which it is substituted and the reactance of the inductances I8 and I9 although they do not materially restrict the flow of direct current they do attenuate the flow of currents of audible frequency between line wires 10 and 18 when contacts 588 and 258 on relay 1E are closed during coding of the line circuit by that field station. The resistance R13 and condenser C13 in series are bridged across the line wires adjacent the inductances I8 and I9 so that they in combination with these inductances may comprise a filter and also may serve to smooth out the impulses created when the line circuit is pulsed by the pulsing relay 1E.

As shown, under all conditions except when field station No. 1 is transmitting an indication the condensers C8 and C14 as well as condensers C9 and C15 are connected in multiple, respectively. This multiple grouping of these condensers results in rather large capacity units around the windings of the line relays at the field stations so that in spite of a large number of these units in series the voice frequency currents can still flow freely. During the transmission of an indication from a particular field station, as for instance from the field station No. 1, the contacts 534 and 535 are open and result in disconnection of the condensers C14 and C15 from the line circuit. Although with the condensers C14 and C15 removed from the line circuit the flow of voice current is somewhat restricted. This restriction is comparatively small because this takes place at only one field station at a time, as a rule at least. In practice the capacity of the condensers C14 and C15 is about twice that of condensers C8 and C9 as a result of which the capacity at this point is reduced to one third upon picking up of the lock-out relay 1LO. The real purpose for reducing the capacity included in series in the line circuit 10-18 beyond the field station that is then sending is to avoid the impulses created by the pulsing relay 1E at such field station from passing to more distant field stations in sufficient quantity to cause operation of line relays at such more distant stations.

Telephone calling key

The telephone selector system superimposed upon the centralized traffic controlling system of our said patent comprising the present invention is the well known Western Electric dispatcher's telephone selecting system which is disclosed in

the patent to Field No. 1,343,256 dated June 15, 1920, and the telephone key illustrated in Fig. 2 of the drawings in a conventional illustration of the key disclosed at the left-hand end in Fig. 7 of said Field patent.

Briefly stated, this telephone coding key K1A includes a coding contact 510 and a code initiating contact 511, a coding wheel 512, a ratchet wheel 513, gears 514 and 515 for driving said coding wheel 512 by said ratchet wheel 513, a centrifugal friction governor including a stationary brake drum 516, centrifugal friction weights 517, a gear 518 and a pinion 519 for driving said friction weights through the medium of the shaft 520 and a lever 521 urged in a counter clockwise direction by a spring 522 and having a pawl 523 for engaging the notches of the ratchet wheel 513, the shaft 520 being connected to and driven by the gear 514. The movable portions of the coding contact 510 and the code initiating contact 511 are pivotally supported by a shaft 525 which shaft is biased in a clockwise direction by a spring 526 to cause the cam 527 to be held against the stop 528. It will be readily seen that as the coding wheel 512 is rotated in a clockwise direction that the cam 527 may be lifted to either an intermediate point to close the code initiating contact 511 or may be moved to a higher point to also close the coding contact 510. The net result is that during each revolution of the coding wheel 512 the code initiating contact 511 is closed through substantially the entire revolution of the coding wheel, whereas the coding contact 510 is intermittently closed to characterize short impulses in accordance with the number of teeth on the coding wheel 512 which are not covered by the guards 530 or 531. For the particular coding wheel illustrated it is readily seen that the coding contact is closed eight times during one revolution of the coding wheel 512 of which the third closure, the sixth and the eighth closure are long, whereas the remaining five closures are short, so that by reason of the fact that each closure results in the picking up of the relay PC and each opening results in the picking up of the relay NC the code consists of nine negative impulses separated by eight positive impulses of which the sixth and the twelfth and sixteenth impulse are long impulses of positive polarity and of which impulse sixteen is extremely long. It should be noted that the first impulse due to closing of contact 511 and in turn contact 603 of relay SRB produces no effect in that the negative pulsing relay NC is already energized. That is, front contact 603 of relay SRB closes before front contact 587 of relay CDTI opens so that no change in line circuit current due to the closing of the impulse circuit at front contact 603 takes place. The code character created thereby is therefore 5-6-4, because the effective fifth, eleventh and fifteenth impulse are long.

In Fig. 1A of the drawings four such coding keys K1A, K1B, K2A and K2B have been conventionally shown. The coding keys K1A and K1B must be adjusted to transmit different codes since they are used for selecting and ringing two different telephone bells at or branched from the same field station. Since keys K2A and K2B select telephones at a different field station they, although they must transmit codes differing from each other, may transmit respectively the same codes as are transmitted by keys K1A and K1B.

Telephone selector and associated telephone apparatus

In Fig. 3 has been illustrated a typical telephone selector unit S1A of the type disclosed in the Field patent above identified; whereas essential parts of this selector have been illustrated in three different stationary positions in Figs. 4, 5 and 6, respectively.

Stating it briefly this telephone selector comprises a ratchet wheel 540 directly connected to a contact carrying pin wheel 541, this pin wheel 541 being biased in a clockwise direction into the normal position, in which position it has been shown in Fig. 3, by a suitable coil spring (not shown). Associated with the ratchet wheel 540 is a ratcheting arm 542 carrying a driving ratchet pawl 543 and a holding ratchet pawl 544, this ratchet arm 542 being pivoted at 545. Directly below the ratchet wheel is a polar armature 547, pivoted at 548, and adapted to be moved from one extreme position to the other extreme position from its neutral biased position, shown in Figs. 3 and 6, depending on the polarity of the current. To this armature 547 is connected an S-shaped operating arm 550 provided with pins 551 and 552, these pins being so located that if the armature 547 moves the S-shaped arm 550 in a clockwise direction the ratchet arm 542 is moved in a counter clockwise direction as is also true if the armature 547 is moved in a counter clockwise direction. In other words, for each operation of the armature 547 from normal, either to the right or to the left, the ratchet arm 542 is moved to the left against the normal bias of the spring 554. It is readily seen that by this construction oscillation of the armature 547 in opposite directions from its normal position about the pivot 548 will cause rotation of the ratchet wheel in a counter clockwise direction so as to be advanced one ratchet tooth corresponding to one pin hole for each energization of the electromagnet 549. This code selector also includes a holding spring 556 located out of the plane of pins 557, 558 and 559 located in the contact carrying pin wheel 541 so that these pins can freely pass by this holding spring 556. The end of this spring 556 is, however, provided with a projecting saddle 560 which is located in the plane of these pins 557, 558 and 559 but normally (see Fig. 3) lies to the left of the circumferential path through which these pins 557, 558, and 559 move during rotation of the pin wheel 541. During intermittent operation of the armature 547, and the ratchet arm 542 intermittently operated thereby, the saddle 560 vibrates at some position to the right of the pins and pin holes but does not get time to reach its full deenergized position shown in Figs. 3 and 6, but upon deenergization of the electro-magnet 549 for an appreciable time the saddle 560 is moved toward the left. If there is then a pin in the path of movement of this saddle toward the left the saddle will be arrested by the pin and the saddle will in turn engage the pin and prevent return of the ratchet wheel 540 to its normal biased position as shown in Fig. 6, but if there is no pin in the path of the movement of the saddle 560 it will return to its normal biased position as shown in Fig. 3. As illustrated the pins 557, 558 and 559 are located in the fifth, the eleventh and fifteenth hole to conform with the code which will be set up by the coding key K1A heretofore described and illustrated in Fig. 2 of the drawings. This holding spring 556 is operated by being engaged by

the roller 542¹ pivoted to the lower end of the ratchet arm 542.

If now the coding key of Fig. 2 were to control the selector illustrated in Fig. 3 the operation of the code wheel 531 (see Fig. 2) would produce a code of sixteen impulses in the line circuit 10-13 of which the fifth and eleventh and the fifteenth impulse are sufficiently long to allow full charging of condenser C7 and deenergization of the electro-magnet 549 for a long period. A long impulse will cause a momentary energization followed by a long deenergization of the magnet 549 because this electro-magnet 549 has included in series therewith the condenser C7. As soon as the condenser C7 becomes fully charged the current through the magnet 549 ceases to flow causing deenergization thereof. It is thus seen that were it not for the pin 557 located in the fifth hole in the pin wheel 541 the ratchet wheel and the associated pin wheel would be returned to their normal biased zero position during the long deenergization of the electro-magnet 549 during the fifth and long impulse of the code, it being understood that both the operating pawl 543 and the holding pawl 544 are disengaged from the teeth of the ratchet wheel 540 during deenergization of the electro-magnet 549 (see Figs. 3 and 6). It is, of course, understood that during quick movement of the armature 547 of the electro-magnet 549 from one extreme through its intermediate biased and to the other extreme position will not allow the ratchet wheel or its associated pin wheel to return toward normal due to the inertia of these wheels. It is thus seen that the code selector illustrated in Fig. 3 will not be allowed to return to its biased position during the long fifth, eleventh and fifteenth impulse of the code, and it should also be understood that there may be many other code selectors connected in multiple with the one shown in Fig. 3 in which the pins 557, 553 and 559 are located in different holes than the fifth, eleventh and fifteenth hole because they have been adjusted to respond to different codes, and therefore the code wheels of these other selectors will be returned to their normal biased position during one or more of the long fifth, eleventh or fifteenth impulses. Since any code wheel that has been returned to its normal position during a long impulse during an intermediate part of a code will not reach its extreme bell ringing position when the total number of fifteen impulses have been transmitted, it is evident that only the code wheel which has its pins located to characterize the same code as the code transmitted will ring a bell. Page 5 of the Field patent above referred to contains a table of all of the possible codes for a fifteen impulse code telephone selector system.

The ratchet wheel 540 is provided with a radially projected arm 562 insulated from the wheel and provided with a contact 563 connected as by a pig tail to a wire 564 leading to the negative pole of a battery 567. This contact 563 is adapted to engage a stationary contact 565 when the pin wheel has been rotated to its fifteenth hole position to close a circuit including the coils 566 of the telephone bell and including the battery 567. The sounding of this bell 569 will of course call the attendant to the telephone which has been conventionally illustrated by the receiver Re and the transmitter Tr. This telephone Re-Tr is rendered effective as soon as the receiver Re is removed from the hook 568, resulting in the closure of one circuit through the transmitter Tr,

the battery 567 and the primary winding of telephone transformer, and closure of another circuit including the condenser C12, receiver Re and the secondary winding of this transformer in series across the telephone line.

Operation

Referring to Figs. 1A and 1B of the drawings let us first assume that an operator at the office illustrated in Fig. 1A desires to operate the track switch (shown in Fig. 7D) located at field station No. 1 shown at the left in Fig. 1B. To accomplish this he moves his switch machine lever SML1 into its right-hand dotted position, thereby connecting the wire leading from the switch machine lever SML1 to the negative line impulsing relay NC instead of to the positive impulsing relay PC. This in itself however does not produce any results because the two circuits leading from the switch machine lever SML1 are open at front contacts 13 and 586 of the code determining relays CD1 and CDT1. Let us now assume that the operator depresses the push button B1 resulting in the closure of contact 38 and the energization of the change relay CH1, the change relay CH1 being obviously energized through a pick-up circuit including the contact 39 of the cancelling push button CNB. With this relay CH1 once energized it will be energized thereafter through a stick circuit including the back contact 49 of the code determining relay CD1. If there is no other change relay CH1 energized at this time the code determining relay CD1 will be energized through a circuit including back contact 41 of relay SC, back contact 42 of relay CF, back contact 43 of series relay CDS, back contact 570 of relay CHT2, back contact 44 of relay CH2, back contact 511 of relay CHT1, front contact 45 of relay CH1, the upper winding of relay CD1, and contact 39 of the cancelling button CNB. With code determining relay CD1 energized it will remain energized through a stick circuit including back contacts 46, 48 and 49 of the relays LV, CO and SC, respectively, in multiple, winding of the series relay CDS, stick contact 47 of the relay CD1, and contact 39 of the cancelling button CNB. Picking up of the series relay CDS by the completion of the stick circuit just traced will prevent the field starting relay CF from being picked up through back contact 51 of the relay CDS, back contact 195 of the relay F and front contact 196 of the relay OR (see Fig. 7A), and will instead pick up the office starting relay CO through the medium of its front contact 51 and the back contacts 50 and 52 of the relays SC and CF.

With the relays CDS and CO now energized the stepping relays V1, V2, V3, V4 and LV will be successively picked up in a manner as described in our said patent and will thereby cause the contacts 64, 63 and 62 of the stepping relays to apply current to one or the other of the pulsing relays PC and NC depending upon the fixedly adjusted position of the jumpers 61, 70 and 72. Upon picking up of the fourth stepping relay V4 the front contact 61 will cause energization of a pulsing relay PN or NC depending on the control impulse to be transmitted which in the present instance is the pulsing relay NC, and through a circuit including front contact 61 of the stepping relay V4, front contact 13 of the code determining relay CD1, and contact 14 to the switch machine lever SML1 assuming its right-hand position.

At the field station (see Figs. 1B, 7C and 7D) the first three successive impulses + + just

transmitted to the field station will cause the station selecting relay ISO (see Fig. 7C) to be maintained energized through front contacts 124, 123 and 32 of the relays V1, V2 and V3 in that order as is determined by the code jumpers 140, 141 and 142 shown in Fig. 7D. On the fourth step, namely, when the stepping relays V4 at the control office and at the field station No. 1 are both energized current of negative polarity is transmitted over the line circuit, as determined by the position assumed by the switch machine lever SML1, as a result of which current is applied through a circuit including contact 30 of the line relay 1F assuming its left-hand position, the front contact 31 of the stepping relay V4 and the lower winding of switch machine control relay SMR1. This causes operation of the contact 182 of this switch machine control relay SMR1 to its left-hand dotted position, resulting in operation of the switch machine SM to its reverse position. During the last step of the code cycle, it being of course understood that in practice a larger number of controls and indicators would be involved than can be accomplished by the five stepping relays illustrated, the stepping relay LV is energized and by lifting of its contact 144 will condition the stick circuit for the station selecting relay so as to be dependent upon front contact 29 of relay 1SB and back contact 138 of relay 1FA, so that as soon as the line circuit is deenergized long enough to cause dropping of the cycle marking relays 1SA and 1SB relay ISO will release. If relay 1FA is, however, picked up in the meantime station selecting relay ISO will release before cycle marking relays 1SA and 1SB release. In the office the picking up of the relay LV on the last step of the C. T. C. code by the opening of its back contact 46 breaks the stick circuit for the code determining relay CDT1 causing dropping of this relay and further causes dropping of the cycle marking relays SA, SB, SC and SD.

Let us now observe how the apparatus functions when it is desired to operate one of the telephone selectors S1A or S1B located at field station No. 1 to call an attendant to the telephone. Referring again to Figs. 1A and 1B, if the operator wishes to establish telephone communication with an attendant located to have access to telephone and selector S1A either with or without changing the position of a control lever for that panel he will depress the telephone push button BT1, thereby causing energization of the change relay CHT1. This change relay when once picked up will be stuck up through a stick circuit including its own front contact 574 and the back contact 575 of the code determining relay CDT1. If no other change relays are then energized the code determining relay CDT1 is energized through a circuit such as heretofore traced for the code determining relay CD1 except that it includes the front contact 571 of the change relay CHT1. With this code determining relay CDT1 picked up a stick circuit therefore is closed including its own stick contact 576, the winding of the relay CDS, and back contacts 46, 48 and 49 of the relays LV, CO and SC, respectively, in multiple. The picking up of the code determining relay CDT1 also causes energization of the code determining repeater relay CDTP1 through the front contact 577 of the relay CDT1. With the code determining repeater relay CDTP1 picked up it closes at its front contact 578 an energizing circuit for the relay OC as soon as the cycle marking relay SB has been picked up to close its front contact 579. 75

This circuit including contacts 578 and 579 performs no particular function at this time, but it prevents the clearing out of the office coding apparatus when a long impulse is applied to the line circuit as will be the case if the operator allows the buzzer to sound for a long time or for reasons explained hereinafter. With the series relay CDS and the relays CO and OC controlled thereby now energized the office apparatus will cause a code to be applied to the line circuit 10-13, all in a manner as determined by the code jumpers 580, 581 and 582 rendered effective through front contacts 583, 584 and 585 respectively, insofar as the first three impulses of the coding cycle, which are the same as when the code determining relay CD1 was energized, are concerned. During the fourth impulse the polarity of the impulse will be determined by the circuit including the front contact 61 of the relay V4, the front contact 586 of the relay CDT1, and the position then assumed by the switch machine lever SML1. In other words, the coding cycle transmitted to the field station when it is desired to establish telephone communication will be exactly the same as when apparatus at such field station is to be controlled up to and including the second last impulse of the code cycle. That is, the apparatus at that field station will be recontrolled in accordance with the positions assumed by the switch control and signal control levers at the office. When the last impulse is transmitted to the field station, namely the impulse that flows when the last stepping relay LV is energized, a special circuit, including the front contact 427 of the stepping relay LV in the office and including the front contact 587 of the code determining relay CDT1, for the pulsing relay NC is closed. This circuit transmits a negative impulse and will remain closed until the operator has operated one of the coding keys K1A or K1B to transmit a telephone selecting code. This long impulse of negative polarity may continue for a very long time depending upon the alertness of the operator.

The operator will be apprised of this long last impulse of the C. T. C. code by the sounding of the buzzer BUZ, which is sounded through the following circuit: beginning at the terminal (+) of a suitable source of current, front contacts 113 and 120 of the relays CO and CF, in multiple, front contact 114 of the last stepping relay LV, front contact 590 of the relay CO, wire 591, back contact 588 of the code initiating relay SRB, wire 595, and front contact 592 of the line repeater relay FA, through the winding of the buzzer BUZ and to the other terminal of said source.

During this sounding of the buzzer BUZ and during the remaining portion of the combined C. T. C. and telephone code cycle the relay VP is maintained energized continuously through the front contact 108 of the stepping relay V4 (see Fig. 7B) and with the relay VP and the relay LV both energized, it being understood that the relay CDTP1 is also now energized, an energizing circuit is closed for the relay E which may be traced from the terminal (+), through the front contact 113 of the relay CO, front contact 114 of the relay LV, front contact 590 of the relay CO, wire 591, front contact 597 of the relay CDTP1, wire 596, front contact 119 of the relay VP, through the winding of the relay E to the other terminal of said source, so that this relay E remains energized to the end of the combined

C. T. C. and telephone selecting and ringing cycle.

In addition to the stick circuit for the relay CDT1 including the stick contact 576 heretofore traced there is a second stick circuit for this relay CDT1 which includes the stick contact 593 of this relay CDT1 and the back contact 594 of the relay SRB. The picking up of the last stepping relay LV at the office by the opening of its back contact 46 breaks the first stick circuit for the code determining relay CDT1 including the stick contact 576.

At the field station No. 1 the last stepping relay LV is also in its energized condition because the station selecting relay 1SO (see Fig. 7C) was still energized when the fourth stepping relay V4 became energized, but the last stepping relay LV at all other field stations will not be energized because the stepping relay V4 at such other field station did not become energized. At station 1, therefore, the last stepping relay LV closes the following energizing circuit for the station telephone selecting relay 1SOT: beginning at the terminal (+) of a suitable source of current, front contact 591 of the relay LV, contact 30 of the line relay 1F assuming its left-hand position, front contact 429 of the relay LV through the winding of the relay 1SOT to the other terminal (-) of this source. Picking up of the telephone station selecting relay 1SOT also closes an energizing circuit for the code initiating relay FRB1 which includes the front contact 503 of the relay 1SOT. With the telephone station selecting relay 1SOT energized and its front contact 506 closed an energizing circuit will be closed for the telephone coding relay FRA1 at one point, this circuit however being open at the contact 505 of the line relay 1F in its left-hand positive polarity position.

Referring now again to the apparatus in the office, it being remembered that the buzzer BUZ is still sounding, let us assume that the operator in response to this sounding of the buzzer operates his telephone key K1A. Referring to Fig. 2 this operation of the telephone key K1A resides in movement of the lever 521 to the horizontal position at which point the pawl 523 engages the next tooth of the ratchet wheel 513. Upon release of the handle 521 it will be gradually returned to its initial position, against the stop 524. This return of the lever 521 to its initial position operates the coding wheel 512 through one complete revolution. During the larger part of the rotation of the coding wheel 512 through one revolution the code initiating contact 511 (see Figs. 2 and 1A) is continuously closed, and although the closure of this contact results in energization of the relay SRB and closure of the contact 603 in the circuit for relay NC this does not produce an impulse because relay NC was already energized. The coding contact 510 is later intermittently closed to characterize a code of fifteen impulses of which the fifth, the eleventh and the fifteenth impulse, created by the third, sixth and eighth tooth respectively, are long. The first two of these long impulses are due to the guards 530 and 531 each making three teeth of the coding wheel equivalent to one long tooth, and the third impulse is due to the uncut part of the coding wheel 512.

Referring now to Fig. 1A it will be observed that closing of the code initiating contact 511, the front contact 593 of the code determining repeater relay CDT1 being closed, closes an energizing circuit for the code initiating relay SRB.

The picking up of the relay SRB closes a stick circuit for the code determining repeater relay CDT1 at the front contact 594 of the relay SRB which includes the front stick contact 599 of the relay CDT1. This lifting of the contact 594 of the relay SRB opens one stick circuit for the code determining relay CDT1 at back contact 594, the other stick circuit for this relay being open at all of the back contacts 46, 48 and 49 of the relays LV, CO, and SC respectively in multiple. The picking up of the code initiating relay SRB closes at its front contact 603 a second circuit for the negative pulsing relay PC but this circuit is still open at back contact 602 of relay CDT1. The code determining relay CDT1 is deenergized by the opening of its second stick circuit including stick contact 593, and by the opening of its contact 587 would remove the long impulses from the line circuit 10-18 were it not for the new circuit for relay NC including back contact 602 of relay CDT1. This new circuit allows the pulsing relays PC and NC to be controlled to transmit the telephone code to the field station by intermittent operation of the telephone code transmitting relay SRA. In other words, intermittent opening and closing of the coding contact 510 of the coding key K1A causes intermittent energization of the code transmitting relay SRA through a circuit including the front contact 600 of the relay SRB, and intermittent operation of the code transmitting relay SRA due to the intermittent closure of its energizing circuit just traced causes alternate energization of the pulsing relays PC and NC through the following circuit:—beginning at the terminal (+) of a suitable source of current, front contact 601 of the relay CDT1, back contact 602 of the relay CDT1, front contact 603 of the relay SRB and the front or the back, as the case may be, contact 604 of the relay SRA. This intermittent operation of the telephone code transmitting relay SRA therefore transmits two impulses for each energization of the relay SRA, that is, transmits eight impulses of positive polarity interspersed by seven impulses of negative polarity making a total of fifteen impulses of which the fifth, eleventh and fifteenth impulse of the positive polarity are long.

Referring now to Fig. 1A of the drawings, these impulses cause operation of all of the polar line relays, such as relays 1F and 2F to alternate energized positions remaining in such positions for longer times during the long impulses. Since, however, only the telephone station selection relay 1SOT is energized the telephone code will only be transmitted to the relay unit RU1 (Fig. 1B) resulting in intermittent energization of the coding relay FRA1. This telephone code will then be retransmitted to line wires 605 and 607 through the medium of pole changer contacts 611 and 612 of the relay coding relay FRA1 and through front contacts 613 and 614 of code initiating relay FRB1. The first five impulses transmitted to selector S1A (see Fig. 3) will ratchet the ratchet wheel 540 to a position where the first pin 557 is in alignment with the saddle 560 fastened to the end of the holding spring 556. Since this fifth impulse is long and since the circuit for the electromagnet 549 includes a condenser C1, the condenser will after the usual impulse time have been fully charged and the flow of current will cease during the remaining part of this long impulse, as a result of which the S-shaped arm 550 is returned to its neutral position shown in Figs. 3 and 6 allowing the ratchet arm 542 to assume its normal biased position.

under which condition both the actuating pawl 543 and the holding pawl 544 will be out of engagement with the ratchet wheel 540 and the holding spring 556 would be allowed to be moved to its normal extreme left-hand position as shown in Fig. 3, were it not for the pin 557 which it engages (see Fig. 6), thereby preventing the return of this pin wheel 541 to its normal biased position. All of the various selectors which do not have five (a pin in fifth hole) for their first digit will return to their normal position. In a similar manner the eleventh impulse which is also long will have resulted in rotating the pin wheel 541 to a position where the pin 558 is engaged by the saddle 560. Since there is only one selector left, namely, selector S1A, which has six for its second digit all but this selector S1A will have returned to their normal position at least once at the end of the second digit of the particular code. The next four impulses, namely the impulses of the third digit will advance the ratchet wheel of selector S1A and its associated pin wheel 541 to fifteenth hole position where the contacts 563-565 close to ring the telephone bell 569. Since this fifteenth impulse is long to the extent of the circuit portion of the code wheel 512, the saddle 560 will engage the third pin 559. During this four impulse digit of which the last impulse is long other selectors will have their pin wheels 541 advanced and others will have them restored to normal but since every selector except selector S1A has lost at least one step, by having been restored to normal at least once during the code, none of these other selectors will have advanced far enough to close their contacts 563-565.

The coding key code wheel 512 makes the fifteenth impulse by closing of its contact 510. The opening of the contact 510 at the end of the ringing time causes a sixteenth impulse by dropping of the relay SRA which in turn causes the transmission of a negative impulse over the line circuit and operation of contact 505 of line relay 1F to the left and dropping of relay FRA1. This results in the sixteenth impulse which kicks the saddle 560 away from pin 559 and allows selector S1A as well as any other selector that has not yet returned to normal, to return to normal. Also, when the arm 527 drops in the notch of the code wheel 512 the contact 511 is opened resulting in deenergization of the relay SRB resulting in deenergization of the relay CDTPI by reason of the opening of its stick circuit at the front contact 584 of the relay SRB. The dropping of the code initiating relay SRB by opening of its front contact 603 results in the deenergization of both of the pulsing relays PC and NC as a result of which the C. T. C. apparatus clears out by the dropping of the cycle marking relays SA, SB, SC and SD and the relays controlled thereby in the control office, which in turn results in the dropping of the cycle marking relays 1SA and 1SB at the field station to cause the C. T. C. apparatus to return to its normal line energized condition.

In a manner similar to that just described the depression of the telephone push button BT2 will, through the medium of the change relay CHT2, energize the code determining relay CDT2 and the code determining repeater relay CDTP2. This will through the medium of the code communicating system result in the energization of the telephone station selecting relay 2SOT at field station No. 2 shown in Fig. 1B of the drawings. This will allow the telephone selectors 75

S2A and S2B to be controlled by the telephone keys K2A and K2B, respectively, in a manner similar to that just described. In this connection it may be pointed out that all of these telephone selectors S1A, S1B, S2A and S2B are identical except that they have their coding pins 557 and 558 located in the proper holes to characterize the proper code. Similarly, these telephone calling keys K1A, K1B, K2A and K2B are identical except that they have by the guards 530 and 531 been set to characterize different codes. Referring to Fig. 2 it will be seen that the guards 530 and 531 may be adjusted to any desired position by the loosening of the cap screw 606 and by rotating these guards about the axis of the code wheel 512 so as to cover certain three tooth groups of teeth to produce a long impulse, after which the cap screw 606 may be again tightened up. Attention is directed to the fact that the codes for coding keys K1A and K2A, for instance, may be set to transmit the same telephone code to a distant field station without interference. This is true because the telephone key K1A can only transmit a telephone code to field station No. 1, whereas the telephone key K2A can only transmit a telephone code to field station No. 2, this being true because the telephone station selecting relays 1SOT and 2SOT can only be energized at a time.

A telephone conversation transmitted by current of voice frequency can be carried on between the telephone TEL0 located at the office and any one of the telephones located at the various field locations at any time, but since the operator has only called one particular telephone the probability is that the attendant at that location only will be in communication with the operator. Also, there is no need of apparatus for a field station attendant to call the operator at the central office because the operator will either have a head set receiver to his ears or will have his telephone connected to a loud speaker so that any field station attendant may speak to him at will without first ringing a telephone bell. As already pointed out the telephone TEL1 and TEL2 located directly at the field location, rather than on some telephone branch extending to some other office as is conventionally shown by the telephone selectors and associated telephones S1A, S1B, S2A and S2B, may have an attendant called thereto through the medium of a telephone bell sounded by the momentary energization of a neutral relay controlled in a similar manner as relay SMR (see Figs. 1B and 7D) is controlled.

This telephone communication between the operator at the office and any one at the various field telephones may be carried on even though the centralized traffic controlling system is then transmitting codes for controlling switches and signals or is transmitting telephone calling codes for sounding the bells at other telephones in a manner as just described, without annoyance due to the code impulses on the line circuit. This is accomplished by the employment of suitable filtering apparatus including a filter FILO located between the telephone set and the coding contacts in the control office, and similar filters used in each of the relay units RU as well as inductors, resistors and condensers at the field locations which also function as filters. This filter FILO is constructed similar to the filter FIL1 constituting part of the relay unit RU1 at field station No. 1, and already described, and for this reason like reference characters have been ap-

plied to like elements of this filter. It may be pointed out that the units of capacity and resistance in series are used to absorb and dissipate high frequency audible pulses created by the pulsing relays PC and NC, the inductances I^1 , I^2 , I^3 and I^4 being employed to prevent these audible frequencies created by these contacts of the impulsing relays from reaching the telephones TEL0, TEL1, TEL2 by having these audible frequencies greatly attenuated. Not only may control codes be transmitted for controlling switches and signals during a telephone conversation, but a field station may also transmit an indication code to the control office without impairing the clearness of the telephone conversation. It is, of course, understood from our said patent that before the transmission of a code indication from a field station to a control office can take place a lock-out relay such as LO1 (see field station No. 1, Fig. 1B) must first be energized, after which the coding is accomplished through the medium of the relay I^E . This lock-out relay LO1 terminates the line at that field station insofar as the flow of direct current or pulsating current of low frequency is concerned, but the telephone conversation will be shunted around this field station through the medium of suitable by-pass means conventionally illustrated by the condensers C8 and C9.

It will be noted that when field station No. 1 transmits an indication code, consisting of impulses varied in length separated by time spaces varied in length through the medium of its impulsing relay I^E , that this coded current flows through the resistance R8 included in series with inductances I^8 and I^9 . This resistance R8 is of substantially the same ohmic value as the resistance of that part of the line circuit 10-18 which has been excluded from the line circuit as now used. The inductances I^8 and I^9 are employed to substantially block, and to a large extent prevent, the flow of telephone current through this shunting branch I^8 , I^9 and R8. The inductance in this shunting branch is divided into two parts I^8 and I^9 to maintain the impedance balance heretofore mentioned and these inductances are located to the left of contacts 258 and 608 so that disturbances generated by the opening of these contacts cannot easily reach the telephone TEL1. At the last field station this line substitute R8- I^8 - I^9 is not necessary since no line circuit including more remote field stations has been excluded. At this station No. 2 the condensers C8 and C9 have also been omitted. The lifting of the contacts of the lock-out relay LO2 will not in any way change the inductance or resistance of the line circuit, it merely including the contacts of the pulsing relays I^E in series in the line circuit. The telephone transformer T2 has its primary winding connected directly in the line circuit through the condenser C11 and at all times permits the flow of telephone audible currents through the primary winding thereof but the coding currents cannot flow through this primary winding. The secondary winding of this transformer T2 is provided with a condenser C12 therein to prevent the coding impulses impressed upon line 10-18 from being audibly noticeable in the telephone circuit 610-618 leading to the telephones and selectors S2A and S2B connected thereto and also to prevent the battery current, at times applied from battery 502¹ to the line wires 610 and 618, flowing through this secondary winding.

In addition to the contacts already referred

to in the specification there are numerous other contacts the purpose of which has been described in our said patent, in view of which it would seem unnecessary to describe the function of these additional contacts.

Referring to Figs. 7A and 7B, the line relay F is provided with contacts 14, 21, 24, 75, 78, 195, 200, 202, and 205. Relay FA is provided with contacts 79, 86, 91 and 592. Relay PC is provided with contacts 16, 20, 17 and 421. Relay NC is provided with contacts 15, 17, 19 and 422. Relay E is provided with contacts 60, 198, 206, 412, 418. Relay EP is provided with contacts 208 and 215. Relay VP is provided with contacts 88, 89, 92 and 119. Relay VI is provided with contacts 87, 95, 100, 101, and 418. Relay V2 is provided with contacts 94, 102, 104, 105 and 117. Relay V3 is provided with contacts 99, 103, 106, 116, and 145. Relay V4 is provided with contacts 93, 107, 108, 109, and 115. Relay LV is provided with contacts 46, 98, 110, 114 and 427. Relay OC is provided with a contact 56. Relay OR is provided with contacts 29, 111, 112, and 196. Relay CF is provided with additional contacts 13, 23, 42, 52, 65, 120, 197, 199, 201, 203, 270 and 271. Relay CO is provided with contacts 12, 22, 48, 54, 58, 76, 97, 113 and 590. Relay SA is provided with contacts 28, 55, and 80. Relay SB is provided with contacts 53, 81, 83 and 579. Relay SC is provided with contacts 41, 49, 50, 66, 75, 82, 85, 90 and 204. Relay SD is provided with contacts 11, 57, 84, and 273. Relay TON is provided with contacts 272, 287, and 417. Relay TOF is provided with contacts 201, 214, and 413. Relay LOF is provided with contact 276. Relay LON is provided with a contact 288.

Referring now to Figs. 7C and 7D, relay I^F is provided with contacts 30, 129 and 505. Relay I^{FA} is provided with contacts 130, 132, 134, 136, 157, 165, 217, 218, 220 and 245. Relay I^{SA} is provided with contacts 154 and 232. Relay I^{SB} is provided with contacts 36, 126, 155, 163, 170, 186, 191, 229, 233, 248 and 414. Relay I^{S} is provided with contacts 187, 226, 237, and 269. Relay I^{OC} is provided with contacts 135, 183, and 227. Relay I^{L} is provided with contacts 35, 121, 185, 192, and 209. Relay I^{LO} is provided with contacts 146, 214, 222, 238, 244, 247, 251, 408, 425, and 546. Relay I^{RL} is provided with contacts 37, 128, 184, and 193. Relay I^{SO} is provided with contacts 125, 131, 133, 137, 156, 164, 216, 221, 236, 415, and 426. Relay I^{SOS} is provided only with contacts 136 and 139. Relay I^{E} is provided with contacts 243, 258, 259, 261, and 608. Relay I^{CH} is provided with contacts 27 and 189. Relay I^{CHP} is provided with contacts 190, 194, 215, 228, 230 and 268. Relay I^{VP} is provided with contacts 160, 162, 167, 234, 241, and 254. Relay V^1 (Fig. 7B) is provided with contacts 34, 124, 159, 172, 175, 176, 210, 224, 253, 262, 410 and 430. Relay V^2 is provided with contacts 33, 123, 169, 177, 179, 211, 239 and 252. Relay V^3 is provided with contacts 32, 122, 174, 178, 212, 251, and 442. Relay V^4 is provided with contacts 31, 121, 152, 168, 189, 213, 249, 250 and 266. Relay LV is provided with contacts 144, 173, 181, 428, 429, 433, and 501. Relay I^{LOF} is provided with contacts 219 and 256. Relay I^{LON} is provided with contacts 246, 263, and 416. Relay T is provided with contacts 26 and 265. Relay M is provided with contacts 25 and 264.

Modification Fig. 8.—If desired the circuit arrangement for the line relay F, the pole changing contacts of the relays PC and NC, the filter FILO

and the contacts 270, 76, and 112 of the relays CF, CO, and OR, respectively, as shown in Figs. 1A and 7B may be arranged so that these elements are interconnected as shown in Fig. 8. The principal difference between the structures of Fig. 7B and Fig. 8 is that the windings of the relay F have been divided into two parts and this relay has been shifted to the line circuit side of the pole changer contacts of the relays PC and NC and the filter FILO and that the stick contact 21 of the relay F shown in Fig. 7B has been omitted. The reason for inserting the line relay F beyond the pole changer contacts and the filter is in order to use the inductance of the line relay F as an additional choke to prevent audible frequency surges due to the operation of these pole changer contacts from reaching the telephone TELO located on the line side of the relay F and to place the relay F at the office under line operating conditions more nearly the same as the line conditions under which the line relays at the field locations operate. That is, the capacitance and inductance of filter FILO modifies the characteristics of the line pulses as they are transmitted through the filter and since it is desirable in the C. T. C. system to have all line relays operate in unison or synchronism as nearly as possible all line relays should be placed on the same side of this filter. It will be seen that in the Fig. 8 arrangement the contacts 270, 76, and 112 of the relays CF, CO, and OR, when closed, merely shunt out the resistance unit R; whereas, in the Fig. 7B construction they also shunt the stick contacts 21 of the line relay F, that is, in the Fig. 7B construction the line circuit cannot be closed at all while the line relay F is down unless one of the contacts 270, 76, or 112 is closed; whereas, in the Fig. 8 construction the line circuit may be closed, even though relay F is down and all of the contacts 270, 76 and 112 are open, but if the line circuit is so closed it will be of rather high resistance by reason of the inclusion of the resistance unit R. In other words, the contacts 270, 76 and 112 serve merely as energy saving contacts since when all are open during periods of rest of the C. T. C. system the line current is substantially reduced. In the Fig. 8 construction, the line relay F as already mentioned is also provided with two windings instead of one, one winding being included in series in each of the line wires. This construction affords a balanced line which is desirable for reasons already pointed out in connection with the line relays 1F and 2F shown in Fig. 1B. It may also be stated here that if desired the line relay F may be of the polar type similar to relays 1F and 2F, the contact structure in this event being modified as conditions require.

The applicants have thus provided a compound code system, so to speak, which enables two different types of direct current codes to be transmitted in succession over the same circuit and received in part by the same decoding apparatus. It should, however, be understood that even though the telephone selector system has been superimposed on a particular and specifically described centralized traffic controlling system that it may be applied to numerous other code type centralized traffic controlling systems disclosed in various patents and pending applications assigned to the common assignee. It should also be understood that the specific disclosure of the present invention has been resorted to for the purpose of disclosing the underlying principles of the invention and its functions rather than the

specific structures preferably used in practicing the invention, and that numerous changes, modifications, and additions may be made in practicing the invention and without departing from the spirit or scope of the invention except as demanded by the scope of the following claims.

What we claim as new is:

1. In a combined code railway traffic controlling system and code telephone selector system, the combination with a centralized traffic controlling system including a central office and a plurality of field stations, a single line circuit connecting said office and stations, a line relay in said office and at each of said stations controlled by current in said line circuit, a telephone calling coding key at said office, traffic controlling code transmitting apparatus at said office and traffic controlling code receiving apparatus at each of said field stations and including said line relays for transmitting a series of distinctive impulses from said office to one of said field stations to characterize a station selecting code and including cycle marking relays at each of said field stations which are maintained energized so long as said line circuit is either intermittently or continuously energized, initiating means at said office to prolong the last impulse of said series and operated in the event it is desired to transmit a telephone selecting code such last impulse being prolonged until a telephone coding key is operated and to thereby maintain said cycle marking relays energized, means including said centralized traffic controlling system and said telephone coding key to transmit a telephone calling code to the selected field station, telephone code decoding means at a field station responsive only if the transmitted code corresponds to the code characterized by such decoding means at such field station and then only if that particular field station has been selected and still has its cycle marking relays energized, and filtering means to allow the flow of voice current around said relays.
2. In a combined code railway traffic controlling system and code call type telephone system, the combination with a centralized traffic controlling system including a central office and a plurality of field stations, a single line circuit connecting said office and stations, a line relay in said office and at each of said stations controlled by current in said line circuit, traffic controlling code transmitting apparatus at said office and traffic controlling code receiving apparatus at each of said field stations and including said line relays for transmitting a series of distinctive impulses from said office to said field stations to characterize a station selecting code which conforms to the code allotted to one field station and including cycle marking relays at each of said field stations which are maintained energized so long as said line circuit is either intermittently or continuously energized, means at said office including a telephone coding key to transmit a telephone selecting code consisting of a second series of impulses the first impulse of which follows the last impulse of said traffic controlling series so closely that said cycle marking relays have not had time to drop down, telephone code decoding means at said one field station and including the associated line relay and cycle marking relays and responsive only to the transmitted telephone selecting code if such transmitted code conforms to the code character of the telephone code decoding means at such field station and then only if that particular field station has been selected and still had its cycle marking relays energized,

and filtering means to allow the flow of voice current around said line relays.

3. In a combined code railway control system and code call system, the combination with a centralized traffic controlling system including a central office and a plurality of field stations, a single line circuit connecting said office and stations, an audible signal in said office, a line relay in said office and at each of said stations all included in series in said line circuit, traffic controlling code transmitting apparatus at said office and traffic controlling code receiving apparatus at each of said field stations and including said line relays for transmitting a series of distinctive impulses from said office to one of said field stations to characterize a code and including cycle marking relays at each of said field stations which are maintained energized so long as said line circuit is either intermittently or continuously energized, means at said office to initiate the transmitting apparatus and prolong the last impulse of said series in the event it is desired to transmit a call code to the same station and to sound said audible signal so long as such impulse is prolonged, and by such prolonging of such impulse maintain said cycle marking relays energized, means including said centralized traffic controlling system and a call coding key to discontinue said prolonged impulse and stop said audible signal and to transmit a calling code to the selected field station, and call code decoding means at such field station responsive only if the transmitted call code corresponds to the code characterized by the call code decoding means at such field station and then only if that perpendicular field station has been selected and still has its cycle marking relays energized.

4. In combination; a central office and a plurality of field stations each having a branch line leading to one or more call stations; a telephone bell for each of said call stations; control apparatus at each of said field stations; a single line circuit connecting said office and each of said field stations; a line relay controlled by current in said line circuit at each of said field stations; code transmitting means including said line circuit and line relays for transmitting a code from said office to any one of said field stations to control apparatus at such station and to connect contacts of the line relay at such station in a circuit for relaying a supplemental code into the branch line extending from that field station; and other code transmitting means at said office for transmitting a supplemental code to any one of each of the call stations on the branch line leading from the selected field station, at which said traffic controlling devices were controlled, through the medium of said line circuit, the line relay at the selected station and the relaying circuit including contacts of such line relay; and decoding means at each of said call stations for decoding the supplemental code and sounding the call bell for that call station which has decoding means conforming to the supplemental code transmitted.

5. In combination; a central office and a plurality of field stations each having a branch line leading to one or more telephone stations; a call bell for each of said telephone stations; control apparatus at each of said field stations; a single line circuit connecting said office and each of said field stations; a line relay controlled by current in said line circuit at each of said field stations; cycle marking relays controlled by said line relays so as to be picked up at the beginning

of a code cycle and so as to remain up so long as said line relays are intermittently or continuously picked up; code transmitting means including said line circuit, cycle marking relays and line relays for transmitting a code from said office to any one of said field stations to control a control device at such station and to connect contacts of the line relay at such station in a circuit for relaying a supplemental call code into the branch line extending from that field station; and other code transmitting means at said office for transmitting a supplemental call code to each of the call stations on the branch line leading from the selected field station, at which said control devices were controlled, through the medium of said line circuit, the line relay at the selected field station and the relaying circuit including contacts of such line relay and front contacts of said cycle marking relays; decoding means at each of said telephone stations for decoding the supplemental code and sounding the call bell for that telephone station which has decoding means conforming to the supplemental call code transmitted; a supplemental connection for each branch circuit for connecting said line circuit to such branch circuit including filtering means which permits the flow of audio telephone current of voice frequency but does not allow the flow of current of either the main or said supplemental code, and a telephone receiver and transmitter at each of said telephone stations for communicating with some one at said office over said supplemental connection.

6. Apparatus for sounding a call bell comprising, a first line circuit connecting a central office and a distant field station, a second line circuit connecting said field station with a call station, a line relay included in said first line circuit at said field station, a plurality of code responsive call selectors at said call station, a station selecting relay at said field station, code transmitting means at said office for transmitting a code cycle consisting of a first series of impulses and a second series of impulses of which the first series characterizes a code by the polarity pattern of its impulses and of which the second series of impulses characterizes a code by the impulse duration pattern of its impulses, means at said field station including said line relay to energize said station selecting relay if the first series of impulses characterizes the code for that field station, and means at said field station including said line relay and said station selecting relay for relaying the second series of impulses into said second line circuit to actuate that one of said code responsive call selectors which responds to the impulse duration code pattern constituting said second series of impulses.

7. In combination, a line circuit connecting a central office and distant station, a polar line relay in said line circuit at said distant station, means at said central office for transmitting a cycle of code impulses over said line circuit consisting of a first series of impulses and a second series of impulses of which the first series characterizes a code by the polarity pattern of the impulses and of which the second series characterizes a code by the impulse duration of the impulses, and decoding means at said distant station responsive only if a cycle of impulses is received of which the polarity code pattern of the first series and the impulse duration pattern of the second series of the transmitted impulses corresponds to the polarity code pattern and impulse duration pattern for that station.

8. In combination; a centralized traffic controlling system comprising a single line circuit connecting a central office and a distant field station, stepping relays at said office and at said field station, normally deenergized cycle marking relays at said central office and at said field stations, means for picking up said cycle marking relays at the beginning of a code cycle and maintaining them energized so long as said line circuit is either intermittently or continuously energized, means for causing the stepping relays at said office and at said field station to be successively picked up in synchronism one for each impulse irrespective of the code character of the impulse effective only if said cycle marking relays are energized, a station selecting relay at said field station, means at said office for transmitting a series of impulses from said office to said station to characterize a code pattern one impulse for each stepping relay picked up, means at said field station to pick up said station selecting relay only if the pattern of code impulses transmitted corresponds to the code pattern assigned to that station, means at said office to specially energize said line circuit and to give a special signal so long as said line circuit is specially energized to thereby maintain said cycle marking relays energized if it is desired to transmit a second series of impulses, a call selector; and means superimposed on said centralized traffic controlling system and including said line circuit and said station selecting relay for removing said specially applied energy, discontinuing said special signal and transmitting a second series of impulses to said call selector and actuate said call selector only if the code pattern of said second series of impulses conforms to the code allotted to said call selector, and then only if said cycle marking relays assumed their energized position upon reception of the first impulse of said second series of impulses.

9. In combination, a central office and a plurality of field stations, a line circuit connecting said office and said field stations, a plurality of code determining relays in said office two for each field station interlocked so that only one of said code determining relays can be energized at one time and effective when energized to initiate the transmission of a code allotted to the corresponding field station, a station selecting relay at each field station, decoding means at each field station for energizing and maintaining energized the station selecting relay at that field station only if a code is transmitted to such field station conforming to the code allotted to that station, a call selector for each field station, means in said office controlled by either of the two code determining relays for a particular field station to transmit a code conforming to the code allotted to that field station and effective if a particular one of such code determining relays is energized for transmitting a code conforming to the code allotted to that station and also transmitting additional impulses to operate a call selector at that station only in the event the station selecting relay and the cycle marking relays for that field station are energized.

10. In a combined code control system and code call system, the combination with a centralized control system including a central office and a plurality of field stations, a station selecting relay for each field station, a single line circuit connecting said office and stations, a line relay in said office and at each of said stations all included in series in said line circuit, con-

trol code transmitting apparatus at said office and control code receiving apparatus at each of said field stations and including said line relays for transmitting a series of distinctive impulses from said office to one of said field stations to characterize a code and including cycle marking relays at each of said field stations which are picked up at the beginning of a code cycle and maintained energized so long as said line circuit is either intermittently or continuously energized, means at said office to prolong the last impulse of said series in the event it is desired to transmit a call selecting code until a call coding key is operated and to thereby maintain said cycle marking relays energized, means including said line circuit, said line relays and said call coding key to transmit a calling code to the selected field station, a call bell at said field station, and call code decoding means at such field station responsive only if the transmitted calling code corresponds to the code characterized by the call code decoding means at such field station for sounding said bell effective only if the station selecting relay for that particular field station is in its energized condition and the associated cycle marking relays are still energized.

11. In a combined code type control system and code type call selector system, the combination with a centralized control system including a central office and a plurality of field stations, a single line circuit connecting said office and stations, a line relay in said office and at each of said stations all included in series in said line circuit, control code transmitting apparatus at said office and control code receiving apparatus including a normally deenergized station selecting relay at each of said field stations and including said line relays for transmitting a series of distinctive impulses from said office to said field stations to characterize a code characteristic of the code of one of said stations and including cycle marking relays at each of said field stations which are picked up at the beginning of a code cycle and are maintained energized so long as said line circuit is either intermittently or continuously energized, means at said office including a call coding key to transmit a call selecting code consisting of a second series of impulses the first impulse of which immediately follows the last impulse of said control code series to avoid deenergization of said cycle marking relays, and call code decoding means at such one field station responsive only to the second series transmitted code impulses if such second transmitted code conforms to the code character of the code call decoding means at such field station and then only if the station selecting relay for that particular field station has been energized and the cycle marking relays for that field station assume their energized position.

12. In a combined code main control system and code call system, the combination with a centralized control system including a central office and a plurality of field stations, a single line circuit connecting said office and stations, a line relay in said office and at each of said stations all controlled by current in said line circuit, main control code transmitting apparatus at said office and traffic controlling code receiving apparatus including a normally deenergized station selecting relay at each of said field stations and including said line relays for transmitting a series of distinctive impulses from said office to said field stations to characterize a code

allotted to one of said field stations and including cycle marking relays at each of said field stations which are maintained energized so long as said line circuit is either intermittently or continuously energized, means at said office to prolong the last impulse of said series in the event it is desired to transmit a call selecting code to the same station and an audible signal together with means to sound the same so long as such impulse is prolonged, and by such prolonging of said last impulse maintain said cycle marking relays energized, means including said centralized main control system and including a call coding key to stop said audible signal and to transmit a calling code to the selected field station, and call code decoding means at a field station responsive only if the transmitted call code corresponds to the code characterized by the call code decoding means at such field station and then responsive only if the station selecting relay for that particular field station was then in its energized position and its associated cycle marking relays were then energized.

13. In combination; a central office and a plurality of field stations each having a branch line leading to one or more call stations; a telephone bell for each of said call stations; a normally deenergized station selecting relay at each field station, control apparatus at each of said field stations; a single line circuit connecting said office and each of said field stations; a line relay controlled by current in said line circuit at each of said field stations; code transmitting means including said line circuit and line relays for transmitting a code from said office to said field stations to control a control device at the particular field station responsive to the station call portion of the code and to cause energization of the station selecting relay at that particular station to thereby connect contacts of the line relay at such station in a circuit for relaying a supplemental code into the branch line extending from that field station; and other code transmitting means at said office for transmitting a supplemental code to each of the call stations over the branch line leading from the selected field station, at which said control devices were controlled, through the medium of said line circuit, the line relay at the selected station and the relaying circuit including contacts of such line relay; and decoding means at each of said call stations for decoding the supplemental code and sounding the call bell for that call station only if that call station has decoding means conforming to the supplemental code transmitted.

14. In combination; a central office and a plurality of field stations each having a branch line leading to a plurality of call stations; a telephone bell for each of said telephone stations; control apparatus at each of said field stations; a normally deenergized station selecting relay at each field station, a single line circuit connecting said office and each of said field stations; a line relay controlled by current in said line circuit at each of said field stations; code transmitting means including said line circuit and line relays for transmitting a code from said office to said field stations to energize the station selecting relay at the particular field station responsive to the transmitted code and to control a control device at such station, said station selecting relay also connecting contacts of the line relay at such station in a bridging circuit for relaying a supplemental code into the branch line extending

from that field station; and other code transmitting means at said office for transmitting a supplemental code to each of the telephone stations on the branch line leading from the selected field station, at which said control devices were controlled, through the medium of said line circuit, the line relay at the selected station and the relaying circuit including contacts of such line relay; decoding means at each of said telephone stations for decoding the supplemental code and sounding the call bell for that telephone which has decoding means conforming to the supplemental code transmitted; a supplemental connection for each branch circuit for connecting said line circuit to such branch circuit including filtering means which permits the flow of audio telephone current of voice frequency but does not allow the flow of current of either the main or said supplemental code, and a telephone receiver and transmitter at each of said telephone stations for communicating with some one at said office over said supplemental connection.

15. Apparatus for sounding a call bell comprising, a first line circuit connecting a central office and a distant field station, a second line circuit connecting said field station with a plurality of call stations, a line relay included in said first line circuit at said field station, a call selector at each of said call stations, a call bell at each of said call stations one for each call selector, a normally deenergized station selecting relay at said field station, code transmitting means at said office for transmitting a code cycle consisting of a first series of impulses and a second series of impulses of which the first series characterizes a code by the polarity pattern of its impulses and of which the second series of impulses characterizes a code by an impulse duration pattern of its impulses, means at said field station including said line relay to energize said station selecting relay if the first series of impulses characterizes the code for that field station, and means at said field station including contacts controlled by said line relay and contacts controlled by said station selecting relay for relaying the second series of impulses into said second line circuit to actuate that one of said call selectors which responds to the impulse duration code pattern constituting said second series of impulses and to sound its associated call bell.

16. In combination, a line circuit connecting a central office and a distant station, a polar line relay in said line circuit at said distant station, means at said central office for transmitting a cycle of code impulses over said line circuit consisting of a first series of impulses and a second series of impulses of which the first series characterizes a code by the polarity pattern of the impulses and of which the second series characterizes a code by the impulse duration of the impulses, and decoding means at said distant station responsive only if a cycle of impulses is received of which the polarity code pattern of the first series and the impulse duration pattern of the second series of the transmitted impulses corresponds to the polarity code pattern and impulse duration pattern for that station, a station selecting relay energized if the first series of impulses characterizes the proper polarity code pattern, and means for sounding a call bell if such station selecting relay is energized and the second series of impulses characterizes the proper impulse duration code pattern.

17. In combination; a centralized traffic controlling system comprising a single line circuit connecting a central office and a distant field station, stepping relays at said office and at said field station, normally deenergized cycle marking relays at said central office and at said field station, means for picking up said cycle marking relays at the beginning of a code cycle and maintaining them energized so long as said line circuit is either intermittently or continuously energized, means for causing the stepping relays at said office and at said field station to be successively picked up in synchronism one for each impulse irrespective of the code character of the impulse effective only if said cycle marking relays are energized, a station selecting relay at said field station, means at said office for transmitting a series of impulses from said office to said station to characterize a code pattern one impulse for each stepping relay picked up, means at said field station to pick up said station selecting relay and maintain it energized only if the pattern of code impulses transmitted corresponds to the code pattern assigned to that station and the line circuit then remains energized, means at said office to specially energize said line circuit and to give a special signal so long as said line circuit is specially energized to thereby maintain said cycle marking relays energized if it is desired to transmit a second series of impulses, a call selector; means superimposed on said centralized traffic controlling system and including said line circuit and said station selecting relay for removing said specially applied energy, discontinuing said special signal and transmitting a second series of impulses, means for actuating said call selector only if the cycle marking relays are energized and the code pattern of said second series of impulses conforms to the code allotted to said call selector, and a call bell sounded if said call selector is actuated.

18. In combination, a central office and a plurality of field stations, a line circuit connecting said office and said field stations, a plurality of code determining relays in said office two for each field station interlocked so that only one of said code determining relays can be energized at one time and each effective when energized to initiate a station selecting code allotted to that field station, a normally deenergized station selecting relay at each field station, decoding means at each field station for energizing and maintaining energized the station selecting relay at that field station only if a code is transmitted to such field station conforming to the code allotted to that field station and if said line circuit is maintained energized, a call selector for each field station, and means in said office controlled by only one of the two code determining relays for a particular field station and effective if energized to transmit a code conforming to the code allotted to the call selector for that station by the transmission of additional impulses to operate the call selector at that station only in the event the station selecting relay for that station is energized.

19. In combination, a central office and a plurality of field stations, a line circuit connecting said office and said field stations, a polar line relay controlled by current in said line circuit at each of said field stations, a plurality of code determining relays in said office two for each field station both effective when energized to initiate a station selecting code for that field station and interlocked so that only one of said

code determining relays can be energized at one time, a normally deenergized station selecting relay at each field station, decoding means at each field station controlled by the polar line relay at such station for energizing and maintaining energized the station selecting relay at that field station through the operation of its polar line relay only if a station selecting code is transmitted to such field station having a polarity code pattern conforming to the code allotted to that station and the line circuit remains energized, a call selector for each field station, and means in said office controlled by either of the two code determining relays for a particular field station for transmitting a code to said line circuit having a polarity code pattern conforming to that station and effective only if a particular one of said two code determining relays is energized to also transmit a code having an impulse duration pattern conforming to the code allotted to the call selector for that station by the transmission of additional impulses to operate the call selector at that station only in the event the station selecting relay for that station is energized.

20. In a code type communicating system, the combination with a line circuit connecting an office and a field station, cycle marking means at said field station which if once energized remains energized so long as said line circuit is continuously energized or is intermittently deenergized by comparatively short intervals of deenergizations irrespective of the polarity of said impulses, a second line circuit connecting said field station and a call station, code responsive receiving means at said call station, means at said field station responsive only if said cycle marking means is energized to retransmit a series of impulses constituting a second code over said second line circuit to control said apparatus at said call station, said code responsive means at said call station being responsive only to a code pattern of impulses including long periods of zero current flow, and means for converting long impulses flowing over said first line circuit into long periods of de-energization of said code responsive receiving means fed over said second line circuit, whereby said cycle marking means is maintained energized during the long periods of deenergization of said code responsive receiving means at said call station.

21. In combination, a code type communication system for sounding a call bell at a call station, a first line circuit extending from a central office to a field station, a second line circuit extending from said field station to said call station, a code responsive means at said call station responsive only to a code including long "off" periods of current separated by one or more short "on" periods of current, a cycle marking relay energized during each period of energization of said first line circuit and deenergized during each period of deenergization of said first line circuit, a station selecting relay at said field station which may be picked up by a multiple impulse code providing an associated cycle marking relay is held energized said code including only short periods of deenergization of said first line circuit, and means controlled by said station selecting relay and said cycle marking relay for energizing the second line circuit during each period of deenergization of said first line circuit.

22. In combination, a code type communication system for sounding a call bell at a call station, a first line circuit extending from a central office to

that particular field station and including contacts of the line relay for that particular station; and means at said central office including said field coding means for transmitting a code having a polarity pattern conforming to the code allotted to that particular field station followed by a code having a current impulse duration pattern

conforming to the code assigned to the call code responsive means for that particular station except that it includes a current "off" period for each alternate impulse of said impulse duration pattern call code.

CERTIFICATE OF CORRECTION.

atent No. 2,259,562.

October 21, 1941.

WILLIAM D. HAILES, ET AL.

It is hereby certified that error appears in the printed specification of the above numbered patent requiring correction as follows: Page 13, first column, line 35, claim 3, for the word "perpendicular" read --particular--; line 40, claim 4, for "telephone" read --call--; page 14, second column, line 53, claim 11, after "series" insert --of--; line 70, claim 12, for "traffic controlling" read --main control--; page 15, first column, line 26, claim 13, for "or or more" read --or more--; line 26-27, for "telephone" read --call--; page 17, second column, line 52, claim 26, strike out "a" before "pattern"; and that the said Letters Patent should be read with this correction therein that the same may conform to the record of the case in the Patent Office.

Signed and sealed this 14th day of December, A. D. 1943.

(Seal)

Henry Van Arsdale,
Acting Commissioner of Patents.
